Primary Examiner — Natasha Vujcic*Assistant Examiner* — Gilbert B Ford(74) *Attorney, Agent, or Firm* — Renner, Otto, Boisselle & Sklar, LLP(57) **CLAIM**

The ornamental design for a vial adapter, as shown and described.

DESCRIPTION

FIG. 1 is a top, right, front perspective view of a vial adapter showing our new design;

FIG. 2 is a front elevation view thereof;

FIG. 3 is a top plan view thereof;

FIG. 4 is a bottom plan view thereof;

FIG. 5 is a cross sectional view taken from the cut-line in FIG. 2 thereof;

FIG. 6 is a bottom, right, rear perspective view thereof; and, FIG. 7 is a bottom, right, front perspective view thereof in an assembled arrangement.

The broken line showing in FIG. 7 is for the purpose of illustrating environmental structure and forms no part of the claimed design.

1 Claim, 7 Drawing Sheets(56)
